UNITED STATES PATENT OFFICE.

RUDOLF KRAUS, OF CORONA, NEW YORK.

CUSPIDOR.

1,052,729.

Specification of Letters Patent. Patented Feb. 11, 1913.

Application filed August 8, 1912. Serial No. 713,988.

To all whom it may concern:

Be it known that I, RUDOLF KRAUS, a citizen of the United States, residing at Corona, county of Queens, and State of New York, 5 have invented a new and Improved Cuspidor, of which the following is a specification.

This invention relates to a cuspidor which does not require to be washed or otherwise 10 cleaned from time to time, and in which the promulgation of germs, etc., owing to insufficient cleaning is entirely excluded, so that the cuspidor is thoroughly sanitary.

In the accompanying drawing: Figure 1 15 is a side view of a cuspidor embodying my invention; Fig. 2 a plan of the shell; Fig. 3 a side view of the shell showing it opened, and Fig. 4 a perspective view of the insert.

The cuspidor comprises essentially a cup-shaped shell or container which is open work and is bulged toward its bottom. The shell is divided longitudinally into two sections 20 10 which are hingedly connected at their lower ends as at 11 and are provided with coating fasteners 12 at their upper ends. 25 By tilting sections 10 upon their hinges, the shell may thus be opened or closed as will be readily understood. Each section is composed of an upper semi-circular rim, a lower 30 similar rim, and a plurality of spaced upright ribs 14 that connect the upper rim to the lower rim. Each rib 14 is formed with a lower convex section which is provided 35 with a radially inwardly extending foot or rest 13 located at a distance above the lower rim. The upper sides of the rests are curved and merge gradually into the inner sides of the ribs, so as to jointly constitute means for

tightly grasping and supporting a correspondingly shaped paper receptacle at a distance above the bottom. 40

With the shell constructed as described, there is adapted to coöperate an insert which consists preferably of a sheet of paper struck up into the form of a bag 15. If desired, 45 the paper forming the bag may be made fire- and water proof. The correlation of the parts is such that the insert may be conveniently grasped by the shell 10 and may be supported on the rests 13 thereof. 50

In use, the shell is opened, the paper bag is inserted and placed upon rests 13 and then the shell is closed to securely sustain the bag in position. By seating the bag at an elevation above the bottom of the shell, the moisture, etc., is prevented from passing through the bag into the shell, or upon the floor, so that cleanliness is insured. Whenever necessary, the bag is removed and thrown away, 60 while a new bag is fitted in position. 55

I claim:

A cuspidor comprising a divided open-work shell composed of an upper sectional rim, a lower sectional rim, a plurality of spaced upright ribs that connect the upper rim sections to the corresponding lower rim sections, said ribs having convex lower portions provided with radially inwardly extending curved rests at a distance above the lower rim, and with a paper bag adapted to 70 be grasped by the ribs and to be seated upon said rests. 65

RUDOLF KRAUS.
